TOOL HANDLE

Herman Feldman, Surfside, and Martin Sams,
Miami Beach, Fla.

Application November 9, 1955, Serial No. 545,878

7 Claims. (Cl. 145—61)

This invention relates to an improved handle for hand tools such as screwdrivers and the like.

In using standard screwdrivers, to take one example of a tool to which the present invention is applicable, it is found on many occasions when a hard driving screw is encountered that the screw becomes so difficult to turn that the leverage afforded one's hand by the standard screwdriver handle is insufficient to turn the screw. On such occasions one is apt to use a pliers or wrench to turn the screwdriver, and then only with clumsy, time consuming difficulty. A number of special purpose screwdriver sets have been heretofore suggested that use wrench handles or ratchet mechanisms to increase the leverage but these, in the main, come in a several piece set that is much too bulky as well as expensive for the average householder to buy or use. It is a desideratum, therefore, to provide a simple one-piece screwdriver that may be used as an ordinary screwdriver but that will furnish means for the extra leverage needed when hard driving screws are encountered.

It has heretofore been suggested, and the structure of the improved handle of the present invention also contemplates and embodies, a tool handle modified by the provision of a through opening extending transversely of the tool handle for the cross-reception of an implement which converts the handle to a T structure and which implement may be grasped by said hand of the user for obtaining the increased operating leverage. In such modified tool handles, as suggested by the prior art, the through opening was usually designed to receive and accommodate a T converting implement of a single cross-sectional dimension, which for this reason limited the scope of usefulness of the tool handle. Where the tool opening is designed as by the use of an elongated handle opening the side walls of which are tapered so as to accommodate converting implements of different cross-sectional areas, other difficulties are encountered such as the lack of secure fitting of the implement in the handle opening (resulting in the shifting of the implement in and the dropping of the implement from the handle) and also resulting in an undesirable see-saw weaving or wiggling of the implement in the handle.

The prime object of our present invention resides in the provision, in a hand tool, of a handle provided as aforesaid with a through opening extending transversely of the handle for the cross-reception of an implement for affording increased operating leverage, said opening being so designed and constructed whereby implements of different cross-sectional areas may be received by said opening and whereby an implement of a given cross-sectional area may be fitted into, held within, and preferably locked by the appropriate structural part of said opening.

To accomplishment of this object and such other objects as may hereinafter appear, our invention relates to the tool handle as sought to be defined in the appended claims taken together with the following specification and the appended drawings, in which:

Fig. 1 is a vertical elevational view of a tool handle

2

embodying the principles of the present invention and shown applied to a screwdriver;

Fig. 2 is a perspective view thereof shown to an enlarged scale with a part cut off in cross-section in the plane of the line 2—2 of Fig. 1;

Fig. 3 is an elevational view of the handle and screwdriver shown in Fig. 1, turned 90° about the axis of the handle, and illustrating the manner in which the tool handle is converted to a T handle;

Fig. 4 is a vertical cross-sectional view of part of the handle shown in Fig. 1 and drawn to an enlarged scale and also illustrating the manner of its use;

Fig. 5 is a view generally similar to Fig. 1 and showing a modification employing a metal liner or insert for the handle opening;

Fig. 6 is a perspective view drawn to an enlarged scale of the metal liner or insert embodied in the handle of Fig. 5;

Fig. 7 is a view similar to Fig. 1 showing a modification thereof;

Fig. 8 is a view also similar to that of Fig. 5 and showing a further modification;

Figs. 9, 10 and 11 are views of further modifications;

Fig. 12 is an explanatory view of these further modifications.

Referring now in more detail to the drawings and having reference first to Figs. 1 to 4 thereof, the tool handle of our invention is shown exemplified in a handle H associated with the shank S of a screwdriver, the handle H being forward or provided adjacent its upper end, where the handle is usually held by the hand of the user for operating the tool, with a through opening O extending transversely of the tool handle for the cross-reception of an implement I (which, for example, may be another available screwdriver) and which latter may be grasped by said hand of the user for converting the handle to a T structure to obtain the needed increased operating leverage. The handle H is preferably made of a material which is somewhat yieldable (capable of flexing) or resilient such as wood or a plastic, for reasons that will become clearer hereinafter.

In accordance with the objects and the principles of the present invention, the through opening O, arranged longitudinally of the handle H, is made to comprise a plurality of openings of sequentially decreasing widths arranged longitudinally of the handle in progressively stepped relation. To accomplish this the opposed longitudinal walls a and b of the opening O are stepped, i. e. formed to provide steps s, s to define a plurality of openings 10, 12, 14 and 16 of sequentially decreasing widths arranged as best indicated in Figs. 1 and 2 of the drawings in progressively stepped relation. To accommodate the largest size of T implement, the opening 10 is formed with an enlarged lead-in or entrant portion e. By means of this construction, implements of different widths may be received by the opening O and an implement of a given width (or area) such as the implement I illustrated in Figs. 3 and 4 may be fitted into and held within one of said stepped openings which is of a corresponding width or area such as the stepped opening 12 illustrated in Figs. 3 and 4.

This opening of stepped formation serves to accomplish a number of results and advantages that imparts the utility desired for a tool handle of this character. Distinguished from a tool handle adapted to receive an implement only of a given dimension or area, the tool handle of the present invention is capable of receiving implements of different cross-sectional areas, any one of which may be fitted for use. If the through opening O were merely tapered to accommodate implements of different widths or areas, the desired end results would not be achievable.

The reasons for this is that in using a through opening in a handle for receiving a T implement for extra leverage, one finds that the most convenient way to hold the handle while driving a hard turning screw is to have one hand holding the tool shank (S) near the blade end (to keep the blade from slipping out of the screw head slot), and the other hand pressing palm down on the top of the handle, the fingers holding the crossed or T implement (to supply the necessary axial pressure); and with a non-stepped through opening it is found that when a T implement is inserted and the operator then begins to turn a hard driving screw in a wall or ceiling position, the user quickly finds that as the handle is rotated and then released to grasp the handle for another turn, the T implement falls out of the opening. This will transpire every time the tool is held at an angle with respect to the ground other than the perfectly vertical position. The inconvenience of having to pick up and replace the T implement after each rotation renders such a construction practically useless. Furthermore, even when held in a position such as the vertical position, the T implement is subject to a see-saw weaving or wiggling in the longitudinally elongated handle opening.

In the structure of the present invention, where hard turning screws requiring extra leverage are encountered, the shank of any other implement I such as the screwdriver illustrated in Figs. 2 and 3 of the drawings is inserted into an opening part which freely receives the same and is then pressed down into the opening part into which it is fitted and held, namely, into one of the stepped openings such as 10, 12, 14 or 16 of a width or dimension corresponding to that of the implement. This action will be further described hereinbelow.

We have found that an important part of the holding effect of the stepped openings is due to the flexing action of the handle walls at the overall opening O. As the T implement shank is pressed into the opening part into which it is to be fitted, there is a tendency of the handle walls at the overall opening to spread due to this flexing action. The sides a and b of the stepped openings may, therefore, be straight or vertical, the distance between the sides being made so that the size of any step is slightly less than the diameter of the T shank for that size step. Consequently, as the T shank is pressed home a minor arc of the cross-section circle of the T shank first engages the top of its particular step; and upon pressing the T shank into its step, the side walls of the overall opening are spread sufficiently to permit the needed flexing with a resultant holding and partly locking engagement of the cross-implement by and between the opposed sides of the receiving step. Tool handles made out of plastic or wood are found resilient enough to be ideal for enabling the needed flexing. To improve the flexing of the handle material in the region adjacent the opening 16, we prefer to provide a cutout or opening portion extending therebelow such as the V-shaped cutout 18 in the handle at this region as clearly shown in Figs. 1, 2 and 4, and the opening portion which extends above the largest stepped opening 10 also serves to improve the flexing at the upper end of the handle.

In the preferred embodiment of the structure, however, it is also desired that the T implement, when fitted into its appropriately stepped opening, may be more securely seated and locked against zigzag or wiggle in the stepped opening into which it is fitted. This we accomplish by having the walls of at least some of the stepped openings recessed to form a locking seat for the cross or T implement. Such a recessed construction may, for example, be formed by having the walls of the stepped openings reversely tapered with reference to the direction of decreasing widths of said openings. As is most clearly shown in Figs. 2 and 4 of the drawings, the walls defining the openings 12, 14 and 16 are recessed such as being reversely tapered so that they have a "keystone" shape in cross-section. With this recessed step or reverse

taper when an implement such as I is pressed down into its stepped opening position, it will "click" into position and it will not only be fitted into and hold within the opening but it will be securely seated and locked against wiggle in the stepped opening, as is most clearly illustrated in Fig. 4 of the drawings, the shanks of the T implement being, of course, locked in place by the recessed wedge sides of the fitted opening.

We have found that there are generally five size divisions of screwdriver shank thicknesses in use, ranging from approximately $\frac{1}{16}$ " diameter to substantially $\frac{1}{8}$ " diameter. In a preferred structure, however, we find that four stepped openings, as illustrated, for shanks ranging from $\frac{5}{16}$ " to $\frac{1}{8}$ ", the stepped intervals being of the order of $\frac{1}{16}$ " in size are adequate for all general uses. We have also found that by providing such defined steps (as distinguished from a continuous taper) we are enabled to reduce the overall length of the opening substantially, this being reducible to approximately one inch in size. A structure such as is illustrated in the drawings will take in T form standard thickness screwdriver shanks from a large size to one of the smallest; and in every case the T screwdriver is not only fitted but is locked in place so firmly that no side-sway or wiggle is possible.

In Figs. 5 and 6 of the drawings, we show a modification of the structure of the invention. In this modification the handle H' is provided with a metal liner or insert L, separately shown in Fig. 6, which is formed with the through opening O', corresponding to the opening O which is formed in the handle itself in the invented form illustrated in Figs. 1 to 4, except that for this modification, the enlarged lead-in or entrant portion is omitted, reliance for the first step (10') being had on the flexing action of the opening walls. This metal liner L is inserted into the corresponding opening in the handle and is swaged or flanged thereto at its opposite ends or is otherwise secured thereto. The inside walls of the metal liner form secure anchoring means for the crossed or T implement and the liner also serves to dress up and therefore improve the appearance of the handle structure. The interior opposed walls a', b' of the metal liner or insert are stepped and preferably recessed in the same manner as illustrated in the form of the invention in Figs. 1 to 4, producing the stepped openings 10', 12', 14' and 16' of which the last three steps are also recessed ones. Fig. 5 of the drawings also illustrates the manner in which implements of any of four different diameters are capable of being fitted into and locked by the four different stepped openings. Again, to improve the flexing of the handle material in the region adjacent the opening 16' we may provide a cutout such as the V-shaped cutout 18 shown in Fig. 1 but which may merely be a slit such as 18' in the handle at this region (see Fig. 5).

In Fig. 7 of the drawings we show another modification of a handle H² in which the stepped openings of the through opening O² points upwardly (instead of downwardly as in the preceding figures), in which case the T implement would be locked with an upward pressure exerted by the fingers of the user. In this structure then the longitudinal walls of the opening O² are stepped to provide the upwardly arranged series of stepped openings 10², 12², 14² and 16². In this modification the walls of the largest opening 10² are also recessed or reversely tapered and this opening is preceded by an enlarged lead-in or entrant portion e².

In the further modification of the invention shown in Fig. 8, the handle H³ is provided with a metal liner or insert L³ which has its interior walls shaped in arcs of decreasing diameters thereby providing openings 10³, 12³, 14³ and 16³ of sequentially decreasing diameters or widths, again arranged longitudinally of the handle in progressively stepped relation. The opening 10³ is here also preceded by the lead-in or entrant portion e³. This form of the invention also provides a recessed construction and one in which the stepped openings are adapted

to receive implements of different circular cross-sections with an accurate and rigid fitting.

In Figs. 9 through 12 we show views of further modifications of the invention, these views showing the same modified construction except that in Fig. 9 the overall opening is made without, while in Figs. 10 through 12, the overall opening is made with a metal liner. The parts in these modifications which are similar to the parts of the previously described views are indicated by similar but suitably primed reference characters. In these modifications, the structure is shown, by way of example, with the stepped openings pointing upwardly (as is also the case in Fig. 7).

Fig. 12 illustrates the flexing action that takes place in the walls of the overall opening O^6 (moving from the full line position to the dotted line position) as the **T** implement I^6 is moved from the entrant portion e^6 to its "clicked in" seated and locked position in the stepped opening 10^6 (the implement moving from the full line position to the dotted line position shown). Each step is recessed differently than in the preceding figures to provide the seating and locking step for the selected **T** implement; and each recessed step is so designed and constructed as to require less force to insert or "click in" the **T** implement than to withdraw it, and to consequently provide for a secure locking and holding of the implement in its seated position even with a small inserting force.

This latter function is accomplished by making the wedge angle of insertion flatter than the wedge angle of withdrawal of the **T** implement. Each step is made to comprise a straight part s followed by a recessed part r , the diameter d (see Fig. 10) of the straight entrant part s being less than the diameter D of the **T** implement for that step. The result is that the inserting angle indicated as n (see Fig. 12) is smaller than the withdrawing angle indicated as n' , these being the respective angles made by the incident tangent to the **T** implement with a vertical drawn at the point of tangency. It will be noted that the force component flexing apart the walls of the opening to permit the insertion of the **T** into the step is a function of the cosine of the inserting angle and that the withdrawal force component is similarly a function of the cosine of the withdrawal angle, with the result that the inserting angle, being smaller, makes it easier to click in the **T** than to withdraw it or click it out. As a consequence, the implement is securely seated in a locked position in the selected step without requiring a large inserting force, or stated otherwise the **T** is capable of being clicked in quite easily, yet it is held so tightly that it cannot be loosened while being used even with the most difficult turning screws.

While in these various modifications of the invention we show the same applied to a screwdriver, it will be understood that the tool handle of the present invention is intended for other tool applications as well, such, for example, as nut drivers, reams, awls, files, universal clip in or chuck handles that take various types of tool shanks (screwdrivers, nut drivers, etc.). In short, any type of rotating tools where it is desired on comparatively irregular occasions to have extra leverage or turning ease may be employed with the handle of the present invention.

The structure, operation, uses and advantages of the tool handle of the present invention will in the main be fully apparent from the above-detailed description thereof. In its application for use with a screwdriver (as an example of the various uses to which the handle may be put) the advantages are apparent. The overall opening, while taking all size **T**'s is small enough to be included in standard size tool handles. On easy turning screws the device may be used like any standard screwdriver. On hard turning screws, where extra leverage is desired, the shank of any implement such as any screwdriver may be readily inserted into the opening of the handle, fitted therewith and locked therein, thus forming a rigid **T** or crossed implement. After use the implement may be readily withdrawn or removed. The handle may be used

by the householder and skilled workman alike. For the householder who usually does not own an expensive special purpose wrench handle tool set, a tool embodying the handle of the invention is an ideal mechanical and economical solution for the problem of extra leverage, especially when any one of a dozen common household items such as screwdrivers, nut drivers, tubing, dowels, icepicks, etc., may be used for the **T** implement. For the skilled workman, who may already own a special purpose wrench handle tool set, the handle of the present invention is of great convenience because it is capable of simple and very rapid use. With no moving parts to wear out or break, the tool handle is rugged and lasting.

While we have shown the tool handle of our invention in its preferred form, it will be apparent that changes may be made in the structure and design thereof without departing from the spirit of the invention defined in the following claims.

We claim:

- 20 1. In a hand tool, a handle adapted to be held by a hand of the user for operating the tool, said handle being provided longitudinally thereof with a through opening extending transversely of the tool handle for the cross-reception of an implement which may be grasped by said hand of the user for obtaining increased operating leverage, the opposed longitudinal walls of said through opening being stepped to define a plurality of openings of sequentially decreasing widths arranged longitudinally of the handle in progressively stepped relation, the said through opening including a portion extending beyond the largest stepped opening and a portion extending beyond the smallest stepped opening, the said longitudinal walls defining said through opening being resilient to permit said walls to flex transversely of the length of said handle, whereby implements of different widths may be received by said through opening and an implement of a given width may be resiliently fitted into and held within one of said stepped openings which is of a corresponding width.
- 25 2. In a hand tool, a handle adapted to be held by a hand of the user for operating the tool, said handle being provided with a through opening extending transversely of the tool handle for the cross-reception of an implement which may be grasped by said hand of the user for obtaining increased operating leverage, the opposed longitudinal walls of said opening being stepped to define a plurality of openings of sequentially decreasing widths arranged longitudinally of the handle in progressively stepped relation, whereby implements of different widths may be received by said opening and an implement of a given width may be fitted into and held within one of said stepped openings which is of a corresponding width, the walls of at least some of said stepped openings being recessed to form an implement seat whereby a selected width implement may be seated and locked against wiggle in the recess-stepped opening into which it is fitted.
- 30 3. In a hand tool, a handle adapted to be held by a hand of the user for operating the tool, said handle being provided with a metal insert formed with a through opening extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, whereby implements of different widths may be received by said opening and an implement of a given width may be fitted into and held within one of said stepped openings which is of a corresponding width, the walls of at least some of said stepped openings of the metal insert being reversely tapered with reference to the direction of decreasing widths of said openings to form an implement seat whereby a selected width implement may be seated and locked
- 35 4. In a hand tool, a handle adapted to be held by a hand of the user for operating the tool, said handle being provided with a metal insert formed with a through opening extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, whereby implements of different widths may be received by said opening and an implement of a given width may be fitted into and held within one of said stepped openings which is of a corresponding width, the walls of at least some of said stepped openings of the metal insert being reversely tapered with reference to the direction of decreasing widths of said openings to form an implement seat whereby a selected width implement may be seated and locked
- 40 5. In a hand tool, a handle adapted to be held by a hand of the user for operating the tool, said handle being provided with a metal insert formed with a through opening extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, whereby implements of different widths may be received by said opening and an implement of a given width may be fitted into and held within one of said stepped openings which is of a corresponding width, the walls of at least some of said stepped openings of the metal insert being reversely tapered with reference to the direction of decreasing widths of said openings to form an implement seat whereby a selected width implement may be seated and locked
- 45 6. In a hand tool, a handle adapted to be held by a hand of the user for operating the tool, said handle being provided with a metal insert formed with a through opening extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, whereby implements of different widths may be received by said opening and an implement of a given width may be fitted into and held within one of said stepped openings which is of a corresponding width, the walls of at least some of said stepped openings of the metal insert being reversely tapered with reference to the direction of decreasing widths of said openings to form an implement seat whereby a selected width implement may be seated and locked
- 50 7. In a hand tool, a handle adapted to be held by a hand of the user for operating the tool, said handle being provided with a metal insert formed with a through opening extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, whereby implements of different widths may be received by said opening and an implement of a given width may be fitted into and held within one of said stepped openings which is of a corresponding width, the walls of at least some of said stepped openings of the metal insert being reversely tapered with reference to the direction of decreasing widths of said openings to form an implement seat whereby a selected width implement may be seated and locked
- 55 8. In a hand tool, a handle adapted to be held by a hand of the user for operating the tool, said handle being provided with a metal insert formed with a through opening extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, whereby implements of different widths may be received by said opening and an implement of a given width may be fitted into and held within one of said stepped openings which is of a corresponding width, the walls of at least some of said stepped openings of the metal insert being reversely tapered with reference to the direction of decreasing widths of said openings to form an implement seat whereby a selected width implement may be seated and locked
- 60 9. In a hand tool, a handle adapted to be held by a hand of the user for operating the tool, said handle being provided with a metal insert formed with a through opening extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, whereby implements of different widths may be received by said opening and an implement of a given width may be fitted into and held within one of said stepped openings which is of a corresponding width, the walls of at least some of said stepped openings of the metal insert being reversely tapered with reference to the direction of decreasing widths of said openings to form an implement seat whereby a selected width implement may be seated and locked
- 65 10. In a hand tool, a handle adapted to be held by a hand of the user for operating the tool, said handle being provided with a metal insert formed with a through opening extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, whereby implements of different widths may be received by said opening and an implement of a given width may be fitted into and held within one of said stepped openings which is of a corresponding width, the walls of at least some of said stepped openings of the metal insert being reversely tapered with reference to the direction of decreasing widths of said openings to form an implement seat whereby a selected width implement may be seated and locked
- 70 11. In a hand tool, a handle adapted to be held by a hand of the user for operating the tool, said handle being provided with a metal insert formed with a through opening extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, whereby implements of different widths may be received by said opening and an implement of a given width may be fitted into and held within one of said stepped openings which is of a corresponding width, the walls of at least some of said stepped openings of the metal insert being reversely tapered with reference to the direction of decreasing widths of said openings to form an implement seat whereby a selected width implement may be seated and locked
- 75 12. In a hand tool, a handle adapted to be held by a hand of the user for operating the tool, said handle being provided with a metal insert formed with a through opening extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, whereby implements of different widths may be received by said opening and an implement of a given width may be fitted into and held within one of said stepped openings which is of a corresponding width, the walls of at least some of said stepped openings of the metal insert being reversely tapered with reference to the direction of decreasing widths of said openings to form an implement seat whereby a selected width implement may be seated and locked

against wiggle in the stepped opening into which it is fitted.

4. In a hand tool, a handle adapted to be held by a hand of the user for operating the tool, said handle being provided with a through opening extending transversely of the tool handle for the cross-reception of an implement which may be grasped by said hand of the user for obtaining increased operating leverage; the opposed longitudinal walls of said opening being stepped to define a plurality of openings of sequentially decreasing widths arranged longitudinally of the handle in progressively stepped relation, and said walls being possessed of an inherent resiliency to permit said walls to flex, whereby implements of different widths may be received by said opening and an implement of a given width may be resiliently fitted into and held within one of said stepped openings which is of a corresponding width, the walls of at least some of said stepped openings being recessed to form an implement seat whereby a selected width implement may be seated and locked against wiggle in the stepped opening into which it is fitted.

5. In a hand tool, a handle adapted to be held by a hand of the user for operating the tool, said handle being provided with a metal insert formed with a through opening extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, said opposed walls being possessed of an inherent resiliency to permit said walls to flex, whereby implements of different widths may be received by said opening and an implement of a given width may be resiliently fitted into and held within one of said stepped openings which is of a corresponding width, the walls of at least some of said stepped openings of the metal insert being recessed to form an implement seat whereby a selected width implement may be seated and locked against wiggle in the stepped opening into which it is fitted.

6. In a hand tool, a handle adapted to be held by a hand of the user for operating the tool, said handle being provided with a metal insert formed with a through opening extending transversely of the tool handle for the cross-reception of an implement which may be grasped

by said hand of the user for obtaining increased operating leverage, the opposed longitudinal walls of said metal insert being stepped to define a plurality of openings of sequentially decreasing widths arranged longitudinally of the handle in progressively stepped relation, said opposed walls being possessed of an inherent resiliency to permit said walls to flex, whereby implements of different widths may be received by said opening and an implement of a given width may be resiliently fitted into and held within one of said stepped openings which is of a corresponding width, the walls of at least some of said stepped openings of the metal insert being reversely tapered with reference to the direction of decreasing widths of said openings whereby a selected width implement may be locked against wiggle in the stepped opening into which it is fitted.

7. In a hand tool, a non-metal handle adapted to be held by a hand of the user for operating the tool, said handle being provided longitudinally thereof with a through opening lined with a metal insert extending transversely of the tool handle for the cross-reception of an implement which may be grasped by said hand of the user for obtaining increased operating leverage, the opposed longitudinal walls of said metal insert being stepped to define a plurality of openings of sequentially decreasing widths arranged longitudinally of the handle in progressively stepped relation, the opposed walls of said through opening including the walls of said metal insert being resilient to permit said walls to flex transversely of the length of said handle, whereby implements of different widths may be received by said through opening and an implement of a given width may be resiliently fitted into and held within one of said stepped openings which is of a corresponding width.
